UNITED STATES PATENT OFFICE

JULIUS THIECKE, OF BERLIN-PANKOW, GERMANY, ASSIGNOR OF TWO-THIRDS TO THE FIRM MINIMAX A.-G., OF BERLIN, GERMANY, A CORPORATION OF GERMANY, AND HERM. HERZOG, OF JAMILITZ, GERMANY

LIQUID-EXPELLING APPARATUS

Application filed September 12, 1927, Serial No. 219,033, and in Germany September 13, 1926.

My invention relates to liquid expelling apparatus in which the liquid is forced out of the apparatus by a gaseous medium under pressure.

5 My improved liquid expelling apparatus consists substantially of a storage receptacle or tank for the liquid, which may be of any suitable construction, and a pressure chamber in which a pressure above atmospheric may 10 be set up by the aid of a quickly burning substance. The gases thus set up and placed under pressure are led into the storage tank where they collect above the liquid in order to force this liquid through suitable ducts 15 and an atomizer or squirting nozzle out of the apparatus. The quickly burning substance or mixture of substances, preferably gun powder or the like contained in a cartridge, may in a preferred form of the apparatus 20 be ignited by a striking pin actuated in known way.

In the drawing affixed hereto and forming part of my specification embodiments of my invention are illustrated by way of example.

25 In the drawing:—

Fig. 1 is a vertical section through my improved liquid expelling apparatus and

Fig. 2 is a similar section through the top portion of the apparatus.

30 Like parts are indicated by like letters of reference in both figures of the drawing.

Referring to the drawing it will be observed that the apparatus consists of a receptacle, tank or container 5 for the liquid

35 and a body or block 6, which may serve as the cover of said receptacle. The pressure gas is generated in a chamber 20 provided in block 6. This chamber is connected with

40 the interior of the receptacle 5 by a tube 15 provided with a non-return valve 15^a at its lower end, so that the gas is obliged to pass

45 through the liquid before it is able to accumulate above the level of the liquid. The liquid is then forced out of the apparatus

through a pipe 16 extending to a point near the bottom of the receptacle 5 and a squirting or atomizing nozzle when a closing member,

such as a cock 19 or valve, in the discharge 50 pipe 16 is opened. If the apparatus is started

by an automatic mechanism, the valve 19 may be omitted.

The mechanism for generating the compressed gas consists in the embodiment illustrated, as shown in Fig. 1, of a barrel 21 inserted into the chamber 20 and serving for the reception of a cartridge 22 containing the propelling medium, a striking pin 23 and a device for driving said striking pin against the cartridge. This device may consist of a hammer 24 and trigger 25, similar to the elements for cocking and firing a gun. The striking pin is guided in a sealing plug 26 screwed into the tapped rear end of the chamber 20 and adapted to be easily removed in order to place a cartridge into the barrel 21. For this purpose the hammer 24 is also mounted on the body or block 6 in an easily detachable manner.

As shown more clearly in Fig. 2, the cartridge 22 contains the priming cap 31 to be ignited by the striking bolt, and at the base a thin layer 27 of a detonating scale powder and beyond the latter, a certain quantity of a sluggishly burning gun-powder 28 in pieces or granules. The cartridge is sealed by a thin disc 29 of cardboard or any other suitable material. On the end of the barrel 21 is placed a cylinder 30 of perforated sheet metal or wire gauze and fixed in position, if desired. This cylinder serves as the combustion chamber for the charge 28.

The charge 28 is ignited by the quickly burning gunpowder priming 27 and projected into the cylinder 30 where it is able, to burn slowly. A gradually rising and uniform pressure is set up in this way which does not subject the material of which the apparatus is constructed to severe stresses. For many purposes it is, furthermore, desirable that the liquid should be slowly discharged from the apparatus.

My improved apparatus, in this instance a fire-extinguisher, operates in the following manner:—

After the cartridge has been fired by drawing and releasing the cock, the pressure generated in the chamber 20 acts through the tube 15 and the valve 15^a upon the contents of the receptacle 5. The products of combus-

tion consisting mainly of carbonic acid gas and nitrogen enter into the extinguishing liquid in the direction of the arrows. The carbonic acid gas passing through the liquid becomes partially or completely dissolved in it and thus aids the extinguishing action of the liquid later on. That part of the carbonic acid gas which does not dissolve in the liquid along with the nitrogen accumulates above the level of the liquid. The pressure in the extinguisher receptacle or tank will then remain substantially unchanged so that the extinguishing liquid may be expelled from the apparatus and squirted on the fire as required by opening the cock 19. The employment of a combustible substance as gas generating medium has the advantage that the medium will remain unchanged for a long time and leakage losses, which are possible when gases under pressure are used, are quite eliminated.

It will be readily understood that the extinguisher itself may have any desired shape and that instead of gunpowder any other substance may be employed which produces compressed gases when burned. The provision of the non-return valve 15^a renders it possible to inert a second cartridge into the barrel should it be found that in extinguishers of great capacity the entire quantity of water has not been discharged from the apparatus by the first cartridge. The mechanism may be employed equally well for other purposes, for instance as an atomizer for liquids used for disinfection or destruction of vermin on plants.

Various modifications and changes may be made without departing from the spirit and the scope of my invention, and I desire, therefore, that only such limitations shall be placed thereon as are imposed by the prior art.

I claim as my invention:

1. In a liquid expelling apparatus of the kind described, a receptacle adapted to contain a liquid, a combustion chamber, communicating means connecting said receptacle and said chamber, a slow burning substance adapted to produce a gas when burned, and means for igniting said substance and projecting it into said chamber.

2. An arrangement for producing pressure gas consisting of a chamber, a cartridge communicating with said chamber, and means for firing said cartridge, characterized by the fact that said cartridge contains a fast burning gunpowder at its base and a slow burning gas-producing substance in its head adapted to be ignited by said fast burning gunpowder and projected into said chamber upon said cartridge being fired.

3. An arrangement for producing pressure gas consisting of a chamber, a cartridge communicating with said chamber, and means for firing said cartridge, characterized by

the fact that said cartridge contains a fast burning gunpowder at its base and a slow burning gunpowder in its head adapted to be ignited by said fast burning gunpowder and projected into said chamber upon said cartridge being fired. 70

4. An arrangement for producing pressure gas consisting of a chamber, a combustion compartment with foraminous walls in said chamber, a cartridge in said chamber and communicating with said combustion compartment, and means for firing said cartridge, characterized by the fact that said cartridge contains a fast burning gunpowder at its base and a slow burning gas-producing substance in its head adapted to be ignited by said fast burning gunpowder and projected into said combustion compartment upon said cartridge being fired. 75 80

In testimony whereof I affix my signature. 85
